UNITED STATES PATENT OFFICE.

EDWARD W. CLARK, OF LOS ANGELES, CALIFORNIA, ASSIGNOR OF ONE-FOURTH TO STANLEY S. TURNER, ONE-FOURTH TO SUSIE M. CLARK, AND ONE-FOURTH TO VIOLET E. TURNER, ALL OF LOS ANGELES, CALIFORNIA.

CORE-BOX FOR PISTONS.

1,378,524.

Specification of Letters Patent. Patented May 17, 1921.

Application filed August 19, 1920. Serial No. 404,675.

To all whom it may concern:

Be it known that I, EDWARD W. CLARK, a citizen of the United States, and a resident of Los Angeles, in the county of Los Angeles, State of California, have invented new and useful Improvements in Core-Boxes for Pistons, of which the following is a specification.

My invention relates to core boxes for casting integral pistons, of the character used in internal combustion engines, and the main object is to provide a core box especially adapted for making cores for pistons having internally formed spiral ribs extending downwardly in the piston from the inner surface of the head to points substantially below the pin bosses, for the purpose of reinforcing the head and walls of the pistons so that a minimum thickness of metal may be provided in said head and walls, thereby substantially reducing the weight of the pistons in the engine cylinders and thus correspondingly reducing vibration, due to the movement thereof at certain speeds.

Reference is had, in the consideration of this application, to other types of core boxes for pistons of my invention, described in two applications for Letters Patent, filed June 30, 1919, Serial No. 309,230; and filed October 31, 1918, Serial No. 261,426.

I may accomplish the above and other objects by means of the mechanism shown in the accompanying drawings, forming a part of this application and appended hereto, in which a single practical embodiment is illustrated, subject to material modification and change, without departing from the spirit of my invention or enlarging its scope beyond that of the appended claims.

In said drawings:

Figure 1 is a side elevation, partly in section of my improved core box mounted upon a suitable base, with the rib forming members shown at their lower extreme of movement in inoperative position.

Fig. 2 is a sectional elevation of the same, with the rib forming members in operative position.

Fig. 3 is a section of Fig. 1 on line 3—3.

Fig. 4 is a section of Fig. 2 on line 4—4.

Fig. 5 is a sectional elevation of the body members in closed position and through the center of the pin bosses.

Fig. 6 is a sectional plan of Fig. 5 on line 6—6.

Fig. 7 is a plan view of the body supporting disk, showing the slots therein for holding the rib forming plates.

Fig. 8 is a section of the same.

Fig. 9 is an elevation, partly in section, of a piston produced by means of my improved core box.

Fig. 10 is an elevation of a core produced by my core box.

In said drawings, B and B' represent like body members which separate at the center and are adapted to be clamped together in the relative positions shown in Fig. 1, said body members having main body molding walls W and W', respectively, corresponding core print molding portions P and P', and diametrically opposite bosses 2, 2, having bores b and b'. Within said body members is a central bore 1 in which the core of sand or the like is adapted to be formed.

The body of the core box is adapted to be positioned as shown in the drawings, with the core print molding portions at the top, the lower end of said body having an opening 3 therein which is adapted to movably receive a circular head molding member H and the upper end of the body has an annular internal bead, or rib r formed thereon which forms a corresponding recess on the periphery of the core and rib on the end of the piston skirt.

Body B—B' is stationarily mounted for use on a base 4 having a stem S removably held in a boss 5 on the upper portion of said base by means of a set screw 6 or otherwise, and a disk, or plate D carried on the upper end of said stem, the body members being suitably attached to said disk by means of dowels d, d, or otherwise.

Head H has a central portion 7 with a plurality of radially formed slots 8, 8, etc., therein and adapted to receive and hold a plurality of spirally formed molding plates R, R, etc. which extend upwardly from portion 7 in spiral leads and are of a maximum width at their lower portions 9 and a minimum width at their upper ends 10. Said plates abut an annular rib A on the upper side of the member 7 and the upper ends thereof, when in molding position, abut the annular rib r of the body, as shown in Fig. 2.

The head may have a suitable extension E at the bottom thereof, also slidably held on the stem S by means of which the rib recess

2
molding elements may be moved from inoperative position shown in Fig. 1 to operative position shown in Fig. 2. A suitable locking device for holding the head at its 5 upper extreme of movement may include a plunger 11 adapted to seat at its inner end 12 in a suitable notch in the stem, and a spring 13 carried on said plunger and attached at opposite ends to extension E and 10 plunger 11 for holding the plunger in engagement with said stem.

The plates R being spirally formed, in order to move the head relative to the body it will be obviously necessary that the lower 15 portion 14 of the body—which is of less diameter than the upper portion in order that extra thickness of metal may be provided at the top of the piston where the piston ring grooves are formed, should have a series 20 of spiral slots 15, 15, etc. formed therein to movably receive the plates P when the head is moved into operative position in the body. Likewise, the stem S has a pair, or more, of spiral grooves 16, 16, formed 25 thereon for movably receiving the inner ends 17 a pair or more of set screws, or pins 18 carried on the extension E. The lead of the plates P, the slots 15 and the grooves 16 correspond, so as to impart a rotary motion 30 to the head H and plates R when the said members are moved upwardly on the stem S by means of the extension E, in a manner similar to the movement of a nut on a screw, except that the lead of the 35 grooves is substantially less than that of the threads on a screw.

It will be clearly understood from a consideration of the drawings that the plates R form corresponding recesses R' in the periphery of the core C; the print molding members P and P' form a core print P' on said core; a reduced portion 14' is provided on the opposite end of the core from said print for providing additional thickness of 45 metal at points opposite the ring grooves in the piston; and the end of the core is provided with an annular rib recess A', formed by the annular rib A on the head H.

Removable pins 20, 20, are provided for 50 insertion in the bores b and b' of bosses 2, 2, and are adapted to extend inwardly into the bore of the body for forming pin boss recesses 2', 2' in the core C. The body members B and B' may be held in proper position by means of dowels 21, held in lugs 22, on member B and seating in similar lugs 55 23, on member B'.

The piston produced by the use of the core C just described has a head H', with relatively thin walls 24 and ring groove carrying portion 14'', a central annular rib a on the inner side of the head, opposite pin bosses 20', a series of spiral ribs R'', R'', etc., and an annular rib r'' at the end of 65 the skirt, as shown in Fig. 9.

In the operation of the core box, it will be understood that when a core has been formed therein and has set for a sufficient length of time to hold together, the plunger 11 may be released from the stem S so as to 70 lower the head H and rib forming plates R into the position shown in Fig. 1. Such movement being rotary and downward, the plates R are stripped from the core in such a manner as to prevent the collapsing of 75 the core and the breaking away of the particles of sand at the rib recesses. When the plates R have been completely withdrawn from the mold, the body members B and B' are then separated and moved horizontally away from the core so as to withdraw the pins 20 from their recesses in the core, after which the core may be removed for use in a casting operation for producing pistons of the character shown and described. 85

What I claim, is:

1. A core box having a stationary body, and a relatively movable member insertible therein including a plurality of spirally formed plates, for forming corresponding recesses in the core produced thereby.

2. A core box having a body, and a relatively movable member therein for forming spiral recesses in the periphery of the core produced thereby.

3. A core box having separable body members and relatively movable means insertible therein for forming spiral recesses in the core produced thereby.

4. A core box having laterally separable body members, and relatively movable means insertible therein, for forming spiral recesses in the core produced thereby.

5. A core box having a body molding portion, and relatively rotatable means insertible therein for forming spiral recesses in the core produced thereby.

6. A core box having a body, and relatively rotatable means for forming spiral recesses in the core and adapted to be inserted 110 and withdrawn from and longitudinally of said body.

7. A core box having a set of separable body members capable of separation and attachment horizontally, and relatively rotatable means for forming spiral recesses in the core and adapted to be moved longitudinally for insertion in and withdrawal from said body.

8. A core box having relatively movable holding members, one of said members having spiral recesses forming means for the core and the other member having corresponding guideways therefor.

9. A core box having a fixed body molding member, means for supporting said body for use, and an internal molding member therefor rotatably and slidably held on said supporting means, as and for the purpose described.

10. A core box having main molding 130

members, and a member insertible therein having a plurality of spiral plates for forming corresponding recesses in the core.

11. A core box having a body molding means, and relatively adjustable recess molding means including a plurality of spiral plates commonly mounted and movable together to and from operative position in said body molding means.

10 12. A core box including an adjustable rotary member having a plurality of spiral recess forming elements held thereon, for the purpose described.

13. A core box including a molding member having a plurality of spiral recess molding elements, and means for guiding said member into and from operative position.

14. A core box including a body molding means, and combined head and recess molding means having a plurality of spiral members, and means in said body molding means for receiving said spiral members.

15. A core box including a supporting structure, a body molding means held thereon, and relatively movable head and recess forming means movable on said support and including a plurality of spiral recess forming members, as described.

16. A core box including relatively stationary and movable molding members, one of said members forming body molding means and the other member forming re-

cesses in the core and having a series of spiral recess molding members adjustable relative to said body.

35

17. A core box including separable body molding means, pin boss molding members detachably held in said body, a core print molding member integral with said body, a head molding member movable in and forming a closure for said body, and a series of spiral molding members carried on said head for forming recesses in the core.

40

18. A core box having relatively adjustable head and body molding members, spiral means for advancing and retracting said head relative to said body, and a series of spiral members movable with said head, for forming corresponding recesses in the core.

45

19. A core box including horizontally movable body members, and a longitudinally movable means longitudinally adjustable relative thereto and including spiral recess forming elements, for the purpose described.

50

20. A core box having horizontally separable body molding members, a fixed support therefor, and longitudinally movable means rotatable on said support when advanced and retracted relative to said body members, for forming spiral recesses in the core.
